UNITED STATES PATENT OFFICE.

HARTWELL R. MOORE, OF BOSTON, MASSACHUSETTS, ASSIGNOR TO THE COMSTOCK, CHENEY & COMPANY, OF IVORYTON, CONNECTICUT.

PIANO-ACTION.

SPECIFICATION forming part of Letters Patent No. 664,168, dated December 18, 1900.

Application filed June 14, 1899. Serial No. 720,446. (No model.)

To all whom it may concern:

Be it known that I, HARTWELL R. MOORE, of Boston, in the county of Suffolk and State of Massachusetts, have invented an Improvement in Piano-Actions, of which the following is a specification, reference being had to the accompanying drawings, in which—

Figure 1 is an elevation of a portion of a piano-action, showing the position of the various parts when the soft pedal is not applied. Fig. 2 is a like elevation showing the position of the parts when the soft pedal is applied.

The object of my invention is to provide means for taking up the lost motion which is present in a piano-action when the soft pedal is applied; and my invention consists in the combination, with the key, hammer-actuating mechanism, the hammer-rail, and the pedal-rod connected with said rail, of a member located between the key and hammer-actuating mechanism, movable bodily between said parts when said rail is moved to take up the lost motion between said parts.

In the drawings, A represents the pedal-rod, which is connected in the usual manner at its lower end with the soft pedal of the instrument and at its upper end with a block a, fast to the movable hammer-rail a', against which latter rests the shank b of hammer B, and the lower end of shank b is fast in block b', which is pivoted to the frame of the instrument. The block b' is engaged by jack c', mounted on pilot-lever c², which also has connected with it the extension c³.

The main feature of this invention is the movable member g, which is made in the form of a wedge and located between capstan d on key D and the lower end of extension c³. Wedge g is pivotally connected with a rail G by a hinge-joint to the frame of the instrument and is movable bodily between extension c³ and capstan d.

The purpose of the bodily-movable wedge g is to take up the lost motion between the key D and extension c³ when the soft pedal of the instrument is operated and rail a' is moved, and in order that wedge g may be moved in the proper direction and at the

proper time a link A' is provided, which is pivotally connected at one end to block a and at its other lower end to rail G.

The operation is as follows: When the soft pedal is applied, rod A is moved endwise and hammer B moved into a position nearer to string M. At the same time that hammer B is moved link A' swings rail G, and thereby moves wedge g bodily in a direction to raise extension c³, pilot-lever c², and jack c', so that jack c' is maintained in proper relation to block b' in both positions of the hammer and there is no lost motion between extension c³ and capstan d.

What I claim as my invention is—

1. In a piano-action the combination of a key; hammer-actuating mechanism; a movable hammer-rail; a pedal-rod; a member movable between the key and hammer-actuating mechanism but not connected with the latter, and means for operating the movable member.

2. In a piano-action the combination of a key; hammer-actuating mechanism; a movable hammer-rail; a pedal-rod; a wedge movable between the key and hammer-actuating mechanism but not connected with the latter, and means for operating the wedge.

3. In a piano-action the combination of a key; hammer-actuating mechanism; a movable hammer-rail; a pedal-rod; a member movable between the key and hammer-actuating mechanism but not connected with the latter, and means connected with the hammer-rail for operating the movable member when the rail is moved.

4. In a piano-action the combination of a key; hammer-actuating mechanism; a movable hammer-rail; a pedal-rod; a wedge movable between the key and hammer-actuating mechanism but not connected with the latter, and means connected with the hammer-rail for operating the wedge when the rail is moved.

HARTWELL R. MOORE.
